UNITED STATES PATENT OFFICE.

CHRISTIAN DORN, OF PHILADELPHIA, PENNSYLVANIA, ASSIGNOR OF ONE-HALF TO WILLIAM G. T. MARCELLUS, OF PHILADELPHIA, PENNSYLVANIA.

EXPANSION-BOLT.

SPECIFICATION forming part of Letters Patent No. 737,555, dated August 25, 1903.

Application filed November 19, 1902. Serial No. 132,023. (No model.)

To all whom it may concern:

Be it known that I, CHRISTIAN DORN, a citizen of the United States, residing in Philadelphia, Pennsylvania, have invented certain 5 Improvements in Expansion-Bolts, of which the following is a specification.

An "expansion-bolt" as that term is used in this specification means a bolt whereby any desired object can be secured to a wall 10 or other surface by means of gripping devices contained in a recess formed in the wall and expanded against the sides of said recess by means of a wedge. Quite a number of devices of this character all having 15 the same principle of operation have been devised and patented and are now in use; and the object of my invention has been to simplify and cheapen the construction of such an expansion-bolt and to reduce the number 20 of parts necessary to its proper operation.

In the accompanying drawings, Figure 1 is a vertical section of an expansion-bolt constructed in accordance with my invention. Fig. 2 is an external view of the parts of the 25 same detached from each other. Fig. 3 is a transverse section on the line *a a*, Fig. 1. Fig. 4 is a transverse section on the line *bb*, Fig. 1; and Fig. 5 is a longitudinal section of a special form of wedge-nut which I sometimes 30 employ.

1 represents part of a wall or other surface to which any desired object is to be attached by means of an expansion-bolt or a number of such bolts, this object in the present instance 35 being a convexed plate or washer 2. In the wall is formed a recess 3 of the proper diameter and depth for the reception of the member of the expansion-bolt, these members comprising in the present instance the wedge-nut 4, the 40 counter-wedge 5, and the screw-bolt 6. In the present instance the opening 3 is of circular form, and the wedge-nut 4 and counter-wedge 5 are externally rounded to correspond with the shape of the opening; but in 45 the event of the opening being of other cross-sectional form the external shape of the wedges can be correspondingly changed. The inclined faces of the wedge-nut 4 and counter-wedge 5 bear upon each other, and the 50 said nut 4 and wedge 5 bear externally upon opposite walls of the opening. Thus, as shown

in the drawings, the nut 4 bears upon the bottom of the opening and the wedge 5 upon the top of the same. Both nut and wedge are ribbed externally, so as to bite into the 55 walls of the opening. The nut 4 has a threaded opening for the reception of the threaded portion of the bolt 6 and is preferably counterbored, as shown at 7, beyond said threaded opening, so as to be free from contact with 60 said threaded portion of the bolt. The counter-wedge 5 has a projecting sleeve 8, and both wedge and sleeve are centrally bored for the reception of the bolt 6, this bore being slightly elongated, as shown in Fig. 4, in 65 order to permit the wedge 5 to slide up and down upon the nut 4, as it is compelled to do in the operation of the device. The outer end of the sleeve 8 bears against the inner face of the plate 2 or other object which is to 70 be secured in position, and the head of the bolt 6 bears upon the outer face of said plate 2. When, therefore, the bolt is turned in the proper direction, the wedge-nut 4 will be drawn forward, and the effect of this action 75 will be to press the outer face of said wedge-nut firmly against one side of the opening 3 and the outer face of the counter-wedge 5 firmly against the other side of said opening. Hence the bolt 6 and the object to be retained thereby will be rigidly held in place, 80 there being a direct outward thrust upon both nut and wedge throughout the entire length of each of them, thus insuring their firm hold upon the walls of the opening. 85 The purpose of the outwardly-extending sleeve 8 is to locate the wedge-nut 4 and counter-wedge 5 so far inwardly from the face of the wall that the latter will offer the proper resistance to expansion and will not be 90 cracked or otherwise injured by the force exerted.

In applying the device the nut 4 and counter-wedge 5 are first placed in the opening. The plate or other object 2 is then properly 95 disposed upon the face of the wall, and the bolt 6 is passed through the opening in said plate and through the central bore of the wedge 5 and its sleeve 8 and is screwed into the threaded opening of the nut 4 until the same 100 has been drawn up against the wedge 5 and the desired expansion has been effected. The

opening in the plate 2 need only be large enough for the reception of the stem of the bolt. Hence the plate is not weakened, as it would be if the opening therein were large enough to permit the nut or wedge to pass through the same.

By using the nut 4 as one of the gripping elements of the device I reduce the number of parts employed and correspondingly cheapen and simplify the construction of the device.

When the wedge-nut has to be made of lead or other soft metal, as is required in some cases, I prefer to cast the same around a nut 4^a of iron or other hard metal, as shown in Fig. 5, so as to avoid the necessity of cutting a thread in the soft metal and at the same time obtain a stronger thread.

Having thus described my invention, I claim and desire to secure by Letters Patent—

1. The combination in an expansion-bolt, of a wedge-nut, and a counter-wedge, each constituting a gripping member of the device, and a bolt passing through said expansion-wedge and adapted to a threaded opening in the wedge-nut, substantially as specified.

2. The combination in an expansion-bolt, of a wedge-nut constituting one of the gripping members of the device and having a threaded opening and a counterbore adjacent thereto, a counter-wedge constituting the other gripping member of the device, and a bolt passing through said counter-wedge and engaging with the threaded opening of the nut, substantially as specified.

3. The combination in an expansion-bolt, of a wedge-nut and a counter-wedge constituting the two gripping members of the device, said counter-wedge having an outwardly-extending sleeve thereon, and a bolt passing through said counter-wedge and its sleeve and engaging with the threaded opening of the wedge-nut, substantially as specified.

In testimony whereof I have signed my name to this specification in the presence of two subscribing witnesses.

CHRISTIAN DORN.
